(57) **CLAIM**

The ornamental design for a fully adjustable air deflector system for snow plow blade, as shown and described.

DESCRIPTION

The present application is related to commonly-owned U.S. Pat. No. 9,551,122, entitled Fully Adjustable Air Deflector System for Snow Plow Blades, issued on Jan. 24, 2017, to commonly-owned U.S. Pat. No. D781,347, entitled Fully Adjustable Air Deflector System for Snow Plow Blades, issued on Mar. 14, 2017, and to commonly-owned U.S. application Ser. No. 12/288,973, now abandoned, entitled Air Deflector for V-Blade Snow Plow, filed on Oct. 24, 2008, which patents and application are incorporated herein by reference in their entireties.

FIG. 1 is a top rear perspective view of the air deflector system of the present invention;

FIG. 2 is a bottom front perspective view thereof;

FIG. 3 is a rear elevation view thereof;

FIG. 4 is a front elevation view thereof;

FIG. 5 is a top view of the air deflector system thereof;

FIG. 6 is a bottom view thereof;

FIG. 7 is a left side view thereof, the right side view being a mirror image thereof;

FIG. 8 is an exploded bottom rear view thereof;

FIG. 9 is an exploded top view thereof;

FIG. 10 is a side view thereof in a first mounting configuration on a plow blade; and,

FIG. 11 is a side view thereof in a second mounting configuration on a plow blade.

The broken lines shown represent environmental subject matter and form no part of the claimed design.
